UNITED STATES PATENT OFFICE

133,902

DESIGN FOR A COMBINED ARMCHAIR AND ASH RECEPTACLE

Harvey W. Rosenblum, Shaker Heights, Ohio

Application December 11, 1941, Serial No. 104,566

Term of patent 7 years

To all whom it may concern:

Be it known that I, Harvey W. Rosenblum, a citizen of the United States, residing in the city of Shaker Heights, county of Cuyahoga, and State of Ohio, have invented a new, original, and ornamental Design for a Combined Armchair and Ash Receptacle, of which the following is a specification, reference being had to the accompanying drawing, forming a part thereof.

Fig. 1 is a perspective view of a combined armchair and ash receptacle, showing my design;

Fig. 2 is an enlarged fragmentary side elevational view of the article;

Fig. 3 is a top plan view of Fig. 2; and
Fig. 4 is a fragmentary end elevational view
thereof.

The dominant feature of my design resides in
the portion shown in full lines.

I claim:

The ornamental design for a combined armchair and ash receptacle, substantially as shown and described.

HARVEY W. ROSENBLUM,
